UNITED STATES PATENT OFFICE

2,173,837

METALLIC CARTRIDGE BELT OR STRIP

Walter T. Gorton, United States Army,
Springfield, Mass.

Application May 6, 1938, Serial No. 206,369

3 Claims. (Cl. 89—35)

(Granted under the act of March 3, 1883, as
amended April 30, 1928; 370 O. G. 757)

The invention described herein may be manufactured and used by or for the Government for governmental purposes, without the payment to me of any royalty thereon.

5 The subject of this invention is a metallic cartridge belt or strip adapted for feeding cartridges into a position to be loaded into the chamber of a gun barrel.

In automatic guns of the type in which a cartridge is pushed directly forward from the belt by the breech bolt it is necessary to pass the belt through the gun in a plane other than the plane of the barrel chamber and breech bolt in order to permit the breech bolt to move into battery. 15 As a result of such arrangement a ramp is usually provided for inclining the cartridge as it is moved forwardly of the breech bolt.

With a view towards permitting a compact construction of the gun with a short stroke for the breech bolt it is proposed in the present invention to provide a belt link or strip which takes advantage of the tapered shoulder of a cartridge to produce an inclination of the cartridge during its initial loading movement.

20 To these and other ends, the invention consists in the construction, arrangement and combination of elements described hereinafter and pointed out in the claims forming a part of this specification.

30 A practical embodiment of the invention is illustrated in the accompanying drawings, wherein:

Fig. 1 is a plan view of a link constructed in accordance with the invention;

35 Fig. 2 is a sectional view through the feed mechanism of a machine gun showing the breech bolt about to push a cartridge out of the belt;

Fig. 3 is a view in rear elevation of the link;

Fig. 4 is a sectional view on the line 4—4 of Fig. 1;

40 Fig. 5 is a longitudinal sectional view showing the normal relation of cartridge and barrel;

Fig. 6 is a similar view showing the position of the cartridge after its initial movement.

45 The link is formed from a metal blank and comprises a web 5, a pair of longitudinally spaced coaxial open rings 6—6 on one side of the web, and a single open ring 7 on the other side of the web and located opposite to the space between the rings 6—6. This arrangement of the open rings is conventional and is made for the purpose of enabling the single ring 7 of one link to fit between the spaced rings 6—6 of an adjoining link so that a cartridge 8 loosely inserted in the aligned links provides a removable pintle connecting the links.

50 The rearmost ring 6 is provided with a pair of fingers 8—8 each having a detent 8a for engaging the cannelure 10 of the cartridge slightly above its center line.

A plurality of resilient and forwardly extending fingers are provided on the front ring 6. Two of the fingers 11—11 are disposed on opposite sides of the ring 6 and are adapted to engage and grip the front part of the cartridge slightly above its center line. A third finger 12 is disposed between the fingers 11—11 and on the lower side of the ring opposite to its open side. The fingers 11 and 12 are formed with offsets respectively 11a and 12a which conform to and engage the 10 tapered shoulder 13 of the cartridge.

Referring to Fig. 6, when a cartridge is fed from the belt into the chamber 14 of a gun barrel by means of a bolt 15, the initial forward displacement of the cartridge results in a vertical movement of the front of the cartridge as the shoulder 13 rides up the offset 12a of the finger 12. This elevation of the cartridge causes it to be released from the grasp of the pair of fingers 11—11 which form a support and guide 15 for the cartridge as it continues its movement into the chamber.

While the invention has been illustrated and described in connection with a disintegrating link it may also be employed with the strip or clip 20 type of cartridge holder.

I claim:

1. A cartridge holder comprising open front and rear rings for holding a cannelured cartridge, a pair of fingers extending forwardly from the 30 front ring for engaging the front end of the cartridge slightly above its center line, and a pair of fingers extending rearwardly from the rear ring for engaging the cannelure of the cartridge 35 slightly above its center line.

2. A cartridge holder comprising open rings for holding a cartridge having a tapered shoulder, a pair of resilient fingers extending forwardly from the front ring for engaging the front end of the cartridge slightly above its center line, said fingers each having an offset for normally engaging the shoulder of the cartridge, and a finger extending forwardly from the front ring between the resilient fingers and on the side of the 40 ring opposite to its opening, said finger having an offset for normally engaging the shoulder of the cartridge.

3. A cartridge holder comprising open rings for holding a cartridge having a tapered shoulder, 50 a pair of resilient fingers extending forwardly from the front ring for engaging the front end of the cartridge slightly above its center line, and a finger extending forwardly from the front ring between the resilient fingers and on the side 55 of the ring opposite to its opening, said finger having an offset for normally engaging the shoulder of the cartridge.

WALTER T. GORTON. 60
